UNITED STATES PATENT OFFICE.

FRANK M. CREIGHTON, OF AMERICUS, GEORGIA, AND WILLIAM E. GRAY, OF MEMPHIS, TENNESSEE, ASSIGNEES TO MOORE DRY KILN COMPANY, OF JACKSONVILLE, FLORIDA, A CORPORATION OF FLORIDA.

DRY KILN.

Application filed April 13, 1926. Serial No. 101,761.

Our invention relates to an improvement in dry kilns and this particular invention pertains to a kiln of so-called "progressive" type.

5 The fundamental object is to provide a kiln in which advantage is taken of the natural circulatory course of the air currents, and in this connection to provide means calculated to accelerate this natural motion of 10 the air through the kiln.

This particular invention includes a heating system, humidifying means arranged to suit the requirements, means for reheating and re-conditioning the air on its return to 15 the drying chamber, from which means it is discharged into the kiln at any desired prearranged point, in an upward direction through the drying chamber, together with auxiliary means for accelerating the natural 20 passage and course of circulation of the air.

More specifically speaking, this invention consists in a drying chamber with suitable heating means and means for humidifying the air, in combination with air intakes and 25 return conduits extending inwardly from the intakes and discharging upwardly into the drying chamber, in a direction suited to the natural course of the air currents from what is termed the "dry" end of the kiln, in 30 the direction of the green end where there is more moisture in the material being treated and a greater amount of humidity in the air, mechanical means being employed at the dry end to accelerate this natural 35 course or cycle of air currents.

In the accompanying drawings:

Figure 1 is a vertical longitudinal section through an illustrative form of my invention, and

40 Figure 2 is a horizontal section.

A represents the drying chamber of the kiln and the numerals 1 represent some approved form of roof ventilators.

A heating system 2 extends longitudinally of the bottom of the kiln and preferably below the rails 3. Various forms of piping for the heating system may be employed, although it is desirable to have an excessive heat at the dry or right-hand end of the kiln as indicated by the three leads of pipes at that end.

Doors 4 are provided at opposite ends and the rails 3 usually slope downwardly from the wet end toward the dry end of the kiln,

they being supported on pillars 5 or other suitable foundation.

An air intake 6 is located at some point in the bottom of the kiln at or near the green end, preferably just inside the door. This is usually covered over by a screen 7 to 60 exclude large particles.

A conduit 8 extends horizontally from the intake 6 toward the opposite end of the kiln, a greater or less distance, according to requirements. While the conduit illustrated 65 is perhaps two-thirds the length of the kiln, obviously it might be much shorter or even longer.

The heated air within the kiln naturally rises from the heating system and moves 70 toward the green end where there is less heat and more moisture, as indicated by the arrows. This air is sucked through the intake 6 and on being re-heated and re-conditioned, issues from the open end of the 75 conduit and rises through the heating system into the drying room A above. Its passage through the conduit is usually facilitated and accelerated by some artificial means such as is illustrated by jets 9 and 80 10, of steam or compressed air or ventilating fans (not shown) might be employed. When jets are employed they are usually located at some distance apart and the location within the conduit is, of course, subject to change 85 to suit the conditions. These jets are supplied from a pipe 11 which has a valve 12 for controlling the two or any number of jets simultaneously and valves 13 and 14 are provided as a means for cutting out any 90 one of these jets, or if there should be a large number of them, several of them. The valve 12 may be regulated by hand control or by control regulators.

At the dry end of the kiln an air intake 95 15 is provided and several short conduits 16, four being shown, with closed inner ends, extend inwardly and are provided with perforations 17 in their upper surfaces for the upward discharge of the air sucked into the intake 15.

A steam spray pipe 18 preferably extends throughout the length of the air intake 15 for humidizing and conditioning the air as it is drawn into the intake. The steam supply to this pipe 18 is controlled by a valve 19 which may be operated by hand or mechanically controlled.

A jet 20 for compressed air or steam is located in the outer end of each of these conduits 16 for creating a suction or partial vacuum in the air intake 15 to cause the air 5 from the extreme dry end of the kiln to flow downwardly into the intake, after which it is discharged through the perforations 17 after being re-conditioned, upwardly into the kiln above as shown by the arrows at 10 the right-hand end of the kiln in Figure 1.

A pipe 21 supplies these nozzles and a hand valve 22 controls the supply for the nozzles 20.

The foregoing mechanism serves as an 15 accelerator for the circulating air at the dry end of the kiln and after re-conditioning it keeps it moving upwardly through the material and onward toward the green end in the natural course of circulation.

20 Humidity spray pipes 23 may be employed wherever most needed. We have illustrated two of these only, one at the top of the green end and the other at the bottom of the dry end. These may be arranged in 25 any way to assist in giving a universal humidity condition and they may be regulated by hand control or control regulators. Thus a constant and substantially uniform agitation of air is in progress throughout 30 the operation of the kiln and this in the natural course of movement of the air, with the result that we attain uniformity of temperatures and humidity throughout the entire interior of the kiln, but at the same time 35 with the ability to add to or subtract from, and otherwise control, the heat, humidity and circulation by the proper manipulation of the various valves. In other words, we attain perfect control of all of these elements or factors.

40 It will be observed that in the operation of this kiln no fresh air is admitted from the outside, the present invention being a means or system of circulation confined to 45 the circulation and re-circulation and conditioning of air wholly inside of the kiln.

In the progressive action of this kiln, advantage is taken of existing natural conditions, and first among these it might be 50 mentioned that the lumber or material being treated is progressively being denuded of its moisture content by the very nature of things. That is to say, the green lumber is placed in the wet end of the kiln, and the 55 last preceding load is moved on into the next zone or area in a slightly dry condition, and the one preceding it is moved forward in a still drier condition, as with the other loads ahead, as the completely cured load is 60 moved at the dry end. Each load occupies a zone of its own, as it were. The air from the more highly heated or dry end, where the curing is approaching completion or is completed, naturally flows in a direction 65 opposite from the progressive movement of

the various loads of lumber or material being treated, toward the denser or less highly heated green end of the kiln, and to facilitate this natural movement of the air, the heated air is accelerated or boosted in 70 the direction of its natural course by the discharge of heated and reconditioned air from the conduits at the bottom of the dry end. And, as fast as the air reaches the green end, it is sucked down and around the 75 larger conduit and reheated and conditioned, and returned. Thus, due to the differential in moisture content at the two ends of the kiln, the ventilating or circulation system and the heat gradient, we obtain a self- 80 regulating means of controlling the humidity throughout the kiln as long as moist steam is liberated at any point. This natural air turn-over tends to give a constant dew point, which is the desideratum in any progressive operation.

85 From the foregoing it will be seen that we get a natural air turn-over in a progressive kiln due to the difference in moisture content at the opposite ends of the kiln, together with the heating system, thus providing a self-regulating means of controlling the humidity throughout the kiln as long as moist steam is liberated at any one 90 point. This natural air turn-over tends to give a constant point of precipitation which is the desideratum in any progressive operation. This condition is facilitated by a gradient of heat between the two ends of the kiln. This gives a differential in density. 95 With these various conditions we direct and control, re-condition, re-circulate, and accelerate the movement of the air currents in their natural cycles of movement through the kilns, thus attaining a high degree of 100 uniformity of heat and humidity throughout, with the result that the curing operation is facilitated and the product treated is 105 uniformly cured.

110 We claim:

1. A kiln of the character described including a drying chamber, a heating system, humidizers, air intakes at opposite ends, a return conduit leading from one air intake and discharging well into the interior of 115 the kiln, a plurality of air conduits extending inwardly from the intake at the opposite end of the kiln and discharging upwardly into the kiln, and means located within the several conduits for creating a suction of air 120 from the kiln into the air intakes, and for causing its discharge therefrom, into the kiln, and valve mechanism for regulating and controlling the passage of air through these conduits.

125 2. A kiln of the character described including a drying chamber, a heating system, humidizers, air intakes at opposite ends, a return conduit leading from one air intake and discharging well into the interior of the 130

5 kiln, a plurality of air conduits extending inwardly from the intake at the opposite end of the kiln and discharging upwardly into the kiln, means located within the several conduits for creating a suction of air from the kiln into the air intakes, and for causing its discharge therefrom, into the kiln, valve mechanism for regulating and controlling the passage of air through these 10 conduits, and humidizing means located at the intake which supplies the return conduits at the dry end of the kiln.

15 3. A kiln of the character described including a drying chamber, air conditioning means for said drying chamber, and means for withdrawing air from the green end of the chamber and directing said air toward the dry end of the chamber, discharging the air in the region of the dry end for natural 20 recirculation toward the green end in a direction opposite to the movement of the material being treated, and means for causing an auxiliary circulation of air at the dry end.

25 4. A kiln of the character described in-

cluding a drying chamber, an air intake extending across the kiln at the green end thereof, and a return conduit leading from said air intake to the region of the dry end for withdrawing air from the green end 30 through the conduit and discharging the air into the dry end of the chamber for natural recirculation back through the kiln in a direction opposite to the movement of the material therethrough.

35 5. A kiln of the character described including a drying chamber, means for conditioning air therein, air intakes approximately at the opposite ends of the kiln, a return conduit leading from one air intake 40 and discharging in the region of the dry end, and a relatively short conduit extending inwardly from the other air intake for creating an auxiliary circulation of air at the dry end.

45 In testimony whereof we affix our signatures.

FRANK M. CREIGHTON.
